UNITED STATES PATENT OFFICE.

ARTHUR BLOXHAM, OF MONTREAL, QUEBEC, CANADA.

ROOF-FLASHING HOLDER.

Application filed June 21, 1926. Serial No. 117,561.

This invention relates to new and useful improvements in flashing holders for roofs and the like, and the object of the invention is to provide a very simple type of holder which will be easily held in place during erection of the building and which when in position will be highly efficient in operation.

Another object is to provide a flashing holder of simple construction for use in the construction of concrete buildings.

In my invention, I provide a flashing holder made of a single piece of material bent to form a receiving channel for the upper edge of the flashing. Part of the material extends beyond the face of the wall, said part being adapted to form a lock for the flashing to hold it in position against the face of the wall. The lower part of the flashing holder lies against the face of the wall and the lower edge of this part is bent upwardly and engages with the material in the wall to lock the holder in position. Reinforcing bars or channels may be provided between the upwardly bent lower edge of the holder and an upwardly turned portion of the guide. Provision is also made for nailing the holder to the wall forms during the course of erection so that on removal of the forms, the holding nails may be easily withdrawn. Lugs are formed in the holder and are bent inwardly to form a gripping means engaging with the material in the wall to prevent movement of the holder. Means are also provided at the back of the holder to ensure that no water will pass into the wall between the uppermost face of the holder and the adjacent portions of the wall.

In the drawings which illustrate one form of my invention;—

Figure 1 is a sectional side elevation of a wall with the flashing holder mounted therein and showing the manner of positioning the flashing during the course of erection of the wall.

Figure 2 is a perspective view of a wall with the flashing and holder in position.

Figure 3 is a front elevation of part of the flashing holder.

Figure 4 is a sectional end elevation taken on the line 4—4 Figure 3.

Figure 5 is a sectional end elevation taken on the line 5—5 Figure 3.

Figure 6 is a side elevation of a wall showing the adaptability of the device when used in step flashing a wall.

Figure 7 is a perspective view of a modified type of holder looking on the back thereof.

Figure 8 is a perspective view looking from the front of the device and showing two holders in overlapped relation.

Figure 9 is an enlarged sectional end elevation taken on the line 9—9 of Figure 7.

Referring more particularly to the drawings, 11 designates a concrete wall which is built in the manner well known in this art, by pouring concrete in its plastic state into forms and then allowing the concrete to set before withdrawing the forms. My improved flashing holder has been designed to suit concrete wall construction and to simplify to a great extent the cost of securing a holder of this class to the wall while it is under construction.

The flashing insert or holder 12 is made from a single sheet of metal, part 13 of which is adapted to align with the face 14 of the wall. Extending at substantially right angles to the part 13 is the guide 15 between the parallel faces 16 of which the upper edge of the flashing 17 is placed. The closed end 18 of the guide consists of two thicknesses of the metal sheet pressed closely together and bent upwardly at an angle to the guide or to the two spaced parallel portions of the sheet forming the guide. The free edge 19 of the uppermost portion of the guide extends beyond the face 14 of the wall and is adapted when bent to lie parallel to said face to act as a locking means for holding the edge of the flashing within the guide.

The lowermost edge 20 of the holder is bent upwardly and inwardly from the face of the wall and also to the portion 13 to form a means for securing the flashing holder to the wall. Extending from the underside of the guide to the inner face of the portion 13, are the channel-shaped reinforcing members 21, the webs 22 of which extend upwardly and over the closed ends of the guide and may be secured thereto by soldering or such like means. The webs may be also soldered to the lower upwardly turned edge of the holder. In Figure 9 I have shown a slightly different method of attaching the reinforcing channels to the holder without the necessity of soldering same. In Figure 9, the webs 22^a of the reinforcing means pass through slots 35, 110

formed in the underside of the closed upwardly turned end of the guide, and between the adjacent faces of said end and then through a slot 36 at the point 37, where 5 the metal forming the guide is doubled over. The webs after passing through the slot 36 are bent over to lie flat against either outer surface of the closed end of the guide, but preferably against the surface 38. In Figure 9, the web 22^a passes through a slot 39 formed in the upwardly turned edge of the holder and is then folded or doubled over to contact with the outer surface of said edge 41. The flanges of the channels are 10 bevelled at their ends 23 and 24 to lie parallel and in contact with the guide, and the innermost face of the portion 13 of the holder, and act as a strut to prevent deformation of the holder during the course 15 of erection of the wall or during transportation of said holders. The reinforcing members are spaced at intervals in the longitudinal direction of the holders to keep same in shape and to form an attaching 20 means for securing the holders to the wall. Punched from the portion 13 of the holders are the dovetailed lugs 25, which extend into the wall to form a further wall attaching 25 means for the holder.

30 The following is a detail of the method of erecting a concrete wall having my improved flashing insert or holder secured thereto. The form, for the face 14 of the portion of the wall shown, is built in sections 26, 27 and 28, the section 27 extending outwardly from the faces of the other sections. In the preferred type of form, section 27 is nailed to the top of section 26 and is made of a thickness equal to the space 35 between the parallel surfaces of the flashing holder to hold said guide in position and to keep same from collapsing during the course of pouring the plastic concrete between the forms. The flashing holder is 40 nailed to the face of section 26, the nails 28^a passing through apertures 29 formed in depressions 30 in the portion 13 of the holder and preferably between the dovetailed lugs. The depressions are positioned 45 near the guides and away from the face of section 26. The depressions are of circular form and to strengthen the portion 13, grooves 31 are formed in the face of the portion 13, each of said grooves communicating at its upper end with a circular depression and extending downwardly therefrom to a point in proximity to the lowermost edge of the holder. The holder is now 50 in position between the forms and is held from movement by nails 28^a. The forms 55 are now ready for receiving the plastic concrete, that is the flashing holder is secured to section 26, section 27 is secured to the upper end of section 26 to hold the parallel portions of the guide apart, and to hold the 60 free edge of the holder in position, while section 28 is mounted above the free edge of the holder. The concrete is then poured in its plastic state between the forms, only one of which is shown in the drawing, the 65 other form being spaced therefrom a distance equal to the thickness of the wall under construction. The concrete flows around the reinforcing members, around the lugs and the guide and also the bottom edge 70 of the holder so that when the concrete is set the holder will be secured to the wall. It will be noticed that the section 27 holds the spaced sides of the guide apart and prevents buckling of same during the forming 75 of the wall. When the concrete is set, the forms are dismantled and in pulling section 26, nails 28 are pulled with it as radially disposed cuts or weakened portions extend outwardly from the nail apertures to allow 80 the head of the nail to pull clear of the holder. The depressions and grooves greatly strengthen the holder in proximity to the nail apertures and prevent distortion of the holder at this point due to the pulling out 85 of the nails. The holders may be made in long lengths reinforced at intervals, or they may be used in the manner shown in Figure 6, that is in short lengths with the uppermost holder spaced from but in overlapping 90 relationship at one end to the holder immediately below it. When used in long lengths the ends 42 of the flashing holder may be cut as shown in Figure 8, that is the corner of the closed end of the guide 95 may be so cut that the adjacent edges of two sections of flashing holders may be in overlapping engagement to form a watertight joint in the simplest and most efficient manner.

100 Many modifications may be made to the device, without departing from the spirit of the invention.

105 The flashing is then placed in the guide and the free end of the holder bent over said flashing to hold it securely in position. It will be seen that a flashing holder built in the manner herein described greatly facilitates the attachment of flashing to concrete walls, roofs and the like. It is simple to 110 construct, and manufacture, and when in position forms a protection for joints between the wall and any horizontally or tapered member adjoining said wall.

115 Having thus described my invention, what I claim is;—

120 1. In wall construction, a flashing holder having a channel guide for the reception of one edge of the flashing, said holder having a portion aligning with the face of the wall, 125 depressions formed in the last mentioned portion, and means formed in the depressions to allow the flashing to be secured by nails to the forms during the construction of the wall, and means formed in the last 130

mentioned means to allow the head of the nails to be withdrawn through the holder when dismantling the forms.

2. In wall construction, a flashing holder having one portion aligning with the wall face and a channel guide extending into the wall, grooves and depressions formed in the part aligning with the wall, nail apertures in said depressions and lines of weakness formed in the depressions and radially disposed from the nail apertures to allow the nail heads to be withdrawn through the flashing holder.

3. A flashing holder according to claim 2, having channel shaped reinforcing means extending between the channel guides and the lowermost edge of the flashing holder, said edge being adapted to engage with the wall, the ends of said reinforcing channels being bevelled to form a support between the surfaces of the holder adjacent thereto.

4. In concrete wall construction, a flashing holder having a portion aligning with the face of the wall, and a channel guide extending at an angle to the said face and into the wall, depressions formed in the first mentioned portion, said depressions extending into the wall, nail apertures formed in the depressions, lines of weakness radiating from said apertures to allow the heads of the nails to be drawn through the holder, lugs formed in the guide to form anchoring means for the holder, said lugs extending into the wall and means for holding the guide at a constant angle to the wall face during the pouring of the concrete used in the construction of the wall.

5. In concrete wall construction and the like, a flashing holder made from a single piece of material and adapted to be inserted in the wall and having a portion of said holder aligning with the face of the wall, a channel guide formed in the holder to receive the edge of the flashing, said guide being angularly disposed to the portion

aligning with the wall, the closed end of said guide being bent upwardly from the main portion of the guide, and reinforcing channels extending between the guide and the lowermost edge of the portion aligning with the wall face, said edge being bent upwardly to grip the wall, one end of each of the webs of said reinforcing channels being bent around the closed end of the guide and secured thereto, while the other end of the reinforcing channels is secured to the lowermost edge of the holder.

6. A flashing holder according to claim 5, having lugs punched from the portion aligning the wall to form positioning means, and depressions formed between the lugs and extending into the wall, said depressions having apertures formed therein for attaching the flashing to the forms used in the construction of the wall.

7. In concrete wall construction and the like, a flashing holder made from a single sheet of material and adapted to be inserted in the wall with a portion flush with the wall face, a channel guide formed in the holder and angularly disposed to the wall face, the closed end of said guide being bent upwardly from the main portion of the guide, and reinforcing channels having their webs extending through slots cut in the closed end of the channel guide and the lowermost edge of the holder, said edge being bent upwardly and inwardly towards the wall face, said webs being doubled over the adjacent portions of the holder to lock the channels in position, and means formed in the face of the holder to allow it to be nailed to a concrete form for the wall, and lines of weakness formed in the last mentioned means to allow the nails to be withdrawn through the holder when the wall is set.

In witness whereof, I have hereunto set my hand.

ARTHUR BLOXHAM.
